UNITED STATES PATENT OFFICE.

WESLEY M. HYDE, OF YOUNGSTOWN, OHIO, ASSIGNOR OF ONE-HALF TO
JOHN ERVEN JOHNSTON, OF MEADE CENTER, KANSAS.

METHOD OF CONSTRUCTING WIRE FENCE.

SPECIFICATION forming part of Letters Patent No. 399,267, dated March 12, 1889.

Application filed September 27, 1888. Serial No. 236,510. (No model.)

To all whom it may concern:

Be it known that I, WESLEY M. HYDE, of Youngstown, in the county of Mahoning and State of Ohio, have invented a certain new and useful Improved Method of Constructing Wire Fence; and I do hereby declare the following to be a full, clear, and exact description of the invention, such as will enable others skilled in the art to which it pertains to make and use the same.

My invention relates to a new method of constructing wire fence of the variety having cross-wires secured to the fence-wires by means of locking plates or washers at the different crossings of the wires.

My improved method consists, essentially, first, in crimping or bending transversely such plates or washers to such extent as will allow the wires to cross each other without bending, the respective crossing-wires being on opposite sides of the plates or washers; second, at one operation straightening such plates or washers and kinking the wires, so that the latter interlock at the central opening of the plates or washers.

In the accompanying drawings is illustrated the manner of carrying out my improved method.

Figure 1 is a side elevation of a section of fence constructed according to my improved method. Figs. 2, 3, 4, 5, and 6 are details hereinafter described.

In Fig. 1, A represents the fence-wires, B the cross-wires, and C the locking plates or washers for securing the cross-wires. As shown, the cross-wires may be arranged in position oblique or at right angles to the fence-wires. The securing-plates may be substantially round washers, or may be square or rectangular, as may be preferred, and different forms may be used on the same fence to give variety—for instance, as shown in Fig.

1. The plates or washers C are bent or crimped transversely either on one line, as shown in Fig. 3, or on two lines and in reverse direction, 45 as shown in Figs. 2 and 4. In either case the crimping is sufficient to allow the wires when applied to opposite sides of the plates to cross each other without bending, as shown in Figs. 2, 3, and 4. The plates after crimping are 50 applied to the fence-wires and the cross-wires are placed in position. Next suitable swages—for instance, such as shown in Fig. 6—are held on opposite sides of the plates C, and by means of pressure or a sharp blow applied to 55 the swages the plates are straightened and the wires kinked, so as to interlock, as shown in Fig. 5. When wires are first kinked and then straightened, they are liable to break, especially the fence-wires that are under strain. 60 With my improved method the wires are slightly kinked and left in this position, and therefore are not liable to be broken.

The plates are crimped in a machine at a trifling expense, and the cross-wires and plates 65 are easily and quickly assembled on the fence, and a single blow is sufficient to straighten the plates and kink the wires.

What I claim is—

The method herein described of constructing wire fence, consisting in first crimping the locking-plates and assembling the parts, and, secondly, in simultaneously straightening or flattening the locking-plates and kinking the wires in opposite direction at their point of 70 crossing, substantially as set forth.

In testimony whereof I sign this specification, in the presence of two witnesses, this 10th day of April, 1888.

WESLEY M. HYDE.

Witnesses:

J. E. JOHNSTON,
P. W. HUBLER.
